(No Model.)

J. E. BOHNER.
ADJUSTABLE SHADE HOLDER.

No. 439,769.

Patented Nov. 4, 1890.

FIG. 1.

ATTEST:

R. Marchand

Geo H. Arthur

INVENTOR:

Joseph E. Bohner,

by

Robert Kline
Attorney.

UNITED STATES PATENT OFFICE.

JOSEPH E. BOHNER, OF CHICAGO, ILLINOIS.

ADJUSTABLE SHADE-HOLDER.

SPECIFICATION forming part of Letters Patent No. 439,769, dated November 4, 1890.

Application filed November 15, 1889. Serial No. 330,467. (No model.)

To all whom it may concern:

Be it known that I, JOSEPH E. BOHNER, a citizen of the United States, residing at Chicago, in the county of Cook and State of Illinois, have invented certain new and useful Improvements in Adjustable Lamp-Shade Holders, of which the following is a specification.

In the type of shade-holders to which the present invention belongs, the holder, rings, or hoops are provided with suspension bars or rods hooked at their upper ends to engage over the top edge or rim of the lamp-chimney and furnish a suspension-support from such point for the holder and shade. In such holders, as heretofore constructed, no provision was made whereby the holder-ring could be adapted to support shades of any other than those having a uniform size or diameter of neck, and consequently different sizes of such holders were necessary to suit the various sizes of shade-necks found on the market; nor was any provision made whereby the holder could be adjusted vertically, so as to compensate for different heights of lamp chimney or shades, and so enable the position of the shade to be adjusted with relation to the flame or light, so as to give the proper and requisite shading.

In the present improvement the above defects are avoided in a very perfect manner, and a shade-holder formed in which a ready and effective adjustment of the shade in a vertical direction can be effected as well as the circumferential contraction or expansion of the holder ring or hoop in a horizontal plane to fit any ordinary size or diameter of shade-neck.

The construction of shade-holder by which I attain the above result is illustrated in the accompanying drawings, in which—

Figure 1 is a perspective view of my improved shade-holder; Fig. 2, a detail sectional elevation illustrating the application of the same; Fig. 3, an enlarged detail horizontal section of the holder ring or hoop, illustrating the means for securing the ring ends together at the required circumferential adjustment; Fig. 4, an enlarged detail elevation of the clip-piece that secures the holder-hoop to the ends of the suspension-arms; Fig. 5, a detail horizontal section, illustrating a modified form

of the means for securing the ends of the holder ring or hoop together; Fig. 6, a detail elevation of one of the suspension-arms, illustrating a modified means for vertically extending or contracting the same, so as to effect a vertical adjustment of the lamp-shade. Fig. 7 is a detail elevation, partly sectionized, of a modified form of the attachment of the shade-supporting arms to the holder-ring.

Similar letters of reference indicate like parts in the several views.

Referring to the drawings, A represents the circular horizontally-arranged holder rim or hoop, and B a series of vertical suspension rods or bars connected thereto, their upper ends being hooked at b to engage over the top rim of the lamp-chimney to support the shade-holder from such point.

In the present invention the ring or hoop A is formed with free or unattached ends, as shown, so as to be capable of a circumferential adjustment to fit the various sizes of shade-necks, as met with in the market. This adjustment may be effected by the spring or elasticity of the ring or hoop itself. I prefer, however, to employ a positive means to secure the ring at its required circumferential adjustment, and such positive attachment may be effected by providing one end of the ring or hoop with a series of perforations a and the other end with an inturned forwardly-projecting hook or tooth a' to engage in the proper one of said perforations to hold the ring to its required circumferential adjustment, as illustrated in Figs. 1 and 3, a rocking movement of said ends upon the tooth a' as a fulcrum being prevented by an inturned lip a² on the one end engaging in one of the perforations in the other end, as shown in Fig. 2. Again, one end of the ring or hoop may be formed with an elongated slot a³ to effect an attachment of the ends of the ring or hoop together, and, if desired, the attachment may be rendered more positive by forming the surface in contact with corrugations, as illustrated in Fig. 5. I do not, however, confine this part of my invention to either of said modes for attaining a positive attachment, as any other well-known equivalent appliance may be substituted therefor without departing from the spirit of my invention.

To enable the suspension-bars B being set equidistantly apart on the holder ring or hoop A in accordance with the expansion or contraction of the same, I connect the same by means of saddle or clip pieces C, slotted so as to embrace the ring or hoop and be capable of being shoved around to the desired circumferential position on said ring. For some forms of holders the bars B may be formed integral with these clips, or riveted thereto. I prefer, however, to attach them in a vertically adjustable or extensible manner thereto, so as to enable the holder ring or hoop A to be adjusted up or down with relation to the flame or light to compensate for different heights of lamp chimney or shades met with in the market, and this vertical adjustment between the parts I prefer to accomplish in the following manner:

20 The lower ends of the suspension-bars R are made with corrugations B' and fit within a vertical cavity or channel in the saddle or clip piece C, the outer wall of which cavity is formed with corrugations c, that correspond with the corrugations on the end of the suspension-bar, so that the two will lock together when brought in contact, and they are held in such condition by the holder ring or hoop A passing through the clip-piece back of the suspension-bar, as clearly illustrated in Figs. 2 and 3. With this construction the clip-piece C is required to be removed from the holder ring or hoop before an adjustment of the parts can be effected. I do not, however, limit this part of my invention to the above means for effecting a relative adjustment between the hooked ends of the suspension-bars and the holder ring or hoop, and any other substitute means for the above may be employed instead without departing from the spirit of my invention. For instance, each of the suspension-bars can be made in two parts b² b³, attached together by a clip b⁴, in which engages the hook or tooth b⁶ on the other part, as clearly indicated in Fig. 6. At their upper ends the arms B are formed with upwardly-extending parts E to constitute a support above the chimney for a vessel for heating water, &c., as indicated in Fig. 3.

50 The supports or shoulders of the holder ring or hoop A, on which the shade rests and is supported, consist in the present invention of a series of arms D, hinged to the pendent ends of the clip C, their body portion being curved outwardly to form outwardly-projecting rests or shoulders d for the lamp-shade; while their free or lower ends are curved inwardly to rest against the lamp-chimney. With this construction the weight of the lamp-shade will always force the free end of the arms D into contact with the sides of the lamp-chimney to afford a firm support for the lower end of the shade-holder and prevent wobbling of the shade and holder in use.

65 In the manufacture of my improved holder the arms D may be hinged directly to the holder ring or hoop A, independent of the

clips C, without departing from the spirit of my invention, and in case where this hinged feature is not required the ring or hoop A can be provided with any of the ordinary forms of fixed arms or shoulders heretofore used, it being preferable in such cases that the arms form an integral part of the clip C.

Having thus fully described my invention, what I claim, and desire to secure by Letters Patent, is—

1. A lamp-shade holder comprising a series of suspension-bars hooked at the upper end to engage over the top rim of the lamp-chimney, outwardly-projecting shade-supporting arms D, and a circular holder ring or hoop attached to the suspension-bars, and formed with unattached ends, so as to be capable of circumferential adjustment to fit different diameters of shade-necks, essentially as herein set forth.

2. A lamp-shade holder comprising a series of suspension-bars hooked at their upper ends to engage over the top rim of the lamp-chimney, a circular holder ring or hoop formed with unattached ends, so as to be capable of circumferential adjustment to fit different diameters of shade-necks, and clip-pieces C, securing the suspension-bars to the holder ring or hoop in a circumferentially-adjustable manner, essentially as herein described.

3. A lamp-shade holder comprising a circular holder ring or hoop and a series of suspension-bars hooked at their upper ends to engage over the top rim of the lamp-chimney, the ring or hoop being made adjustable in a vertical direction with relation to the hooked ends of the suspension-bars, in the manner substantially as described, and for the purpose set forth.

4. A lamp-shade holder comprising a series of suspension-bars hooked at their upper ends to engage over the top rim of the lamp-chimney, a holder ring or hoop formed with unattached ends, so as to be capable of circumferential adjustment to fit different diameters of shade-necks, and clip-piece C, sliding on the ring or hoop and having vertical channels to receive the lower ends of the suspension-bars, the ends of such arms and the outer walls of the channels being corrugated, and the holder-hoop arranged to pass through the clip at the rear of the suspension-arms, essentially as set forth.

5. A lamp-shade holder comprising a series of suspension-bars hooked at their upper ends to engage over the top rim of the lamp-chimney and a circular holder ring or hoop attached thereto and formed with unattached ends, so as to be capable of circumferential adjustment to fit different diameters of the shade-necks, the one end being provided with a series of perforations a and at the other with an inturned forwardly-extending tooth a', essentially as set forth.

6. A lamp-shade holder comprising a series of suspension-bars hooked at their upper

ends to engage over the top rim of the lamp-chimney and a circular holder ring or hoop attached thereto and formed with unattached ends, so as to be capable of circumferential adjustment to fit different diameters of the shade-necks, the one end being provided with a series of perforations a and at the other an inturned forwardly-extending tooth a' and an inturned lip a'' , adapted to engage different perforations a , essentially as set forth.

7. A lamp-shade holder comprising a series of suspension-bars hooked at their upper ends to engage over the top rim of the lamp-chimney and extending upwardly to form

projections E, that constitute a support for a vessel for heating water, &c., and a circular holder ring or hoop attached to said arms and formed with unattached ends, so as to be capable of circumferential adjustment to fit different diameters of shade-necks, essentially as set forth.

In testimony whereof witness my hand this 12th day of November, 1889.

JOSEPH E. BOHNER.

In presence of—

GEORGE BOHNER,
ROBERT BURNS.
